[57] CLAIM

The ornamental design for carrier for mounting on bicycles, as shown and described.

DESCRIPTION

FIG. 1 is a perspective view of a carrier for mounting on bicycles showing my new design;

FIG. 2 is a side elevation view thereof, the other side being a mirror image;

FIG. 3 is an end elevation view thereof;

FIG. 4 is a top plan view thereof;

FIG. 5 is an end elevation view taken from the other end thereof; and,

FIG. 6 is a bottom plan view thereof.

FIG.1

FIG.4

FIG.2

FIG.3
